UNITED STATES PATENT OFFICE.

ALBERT M. WHITE, OF WATERBURY, CONNECTICUT, ASSIGNOR TO THE
PATENT BUTTON COMPANY, OF SAME PLACE.

RIVET-SETTING MACHINE.

SPECIFICATION forming part of Letters Patent No. 394,743, dated December 18, 1888.

Application filed May 24, 1888. Serial No. 274,996. (No model.)

To all whom it may concern:

Be it known that I, ALBERT M. WHITE, of Waterbury, in the county of New Haven and State of Connecticut, have invented a certain 5 new and useful Improved Rivet-Setting Machine, of which I declare the following to be a full, clear, and exact description, reference being had to the accompanying drawings, forming part of this specification.

10 This invention relates to improvements in rivet-setting machines in which the rivets are conveyed by a chute to a receiver, where they are held in position to be driven by the plunger; and the invention consists of a rivet-setting machine having its receiver constructed substantially as described and claimed.

In the accompanying sheet of drawings, Figure 1 is a side elevation of a portion of the machine, showing the receiver in section; 20 Fig. 2, a plan view of the receiver; Fig. 3, a front view of the receiver, partly in section in the plane xx ; Fig. 2; Fig. 4, a plan view of the separator and a portion of the chute; Fig. 5, a cross-section in the plane xx , Fig. 4; Fig. 25 6, an edge view of the chute and separator.

Similar letters of reference indicate like parts in the several figures.

It is essential in the rivet-setting machines to which this improvement is adapted that the 30 rivets should pass one by one and at regular intervals from the chute into the receiver, so that each time the plunger rises after having driven a rivet another rivet will be deposited in the receiver ready to be driven by the 35 plunger when it again descends. Each rivet drops into the receiver with its piercing end downward, and is so held by the receiver to await the action of the plunger. The receiver is constructed at the outer end of an arm, A, 40 bolted to the frame B of the machine. This arm terminates in a block of suitable thickness, in which is formed a cylindrical perforation, a , with a channel, b , opening into it from the rear. In the edges of the block on each 45 side, and in range with the perforation a , are cut recesses, in which are pivoted guides c . These guides extend under the arm A and form a conical-shaped bottom, closing or 50 nearly closing the perforation a , and they are provided with wings or arms d and connected near their lower extremities by a spring, e .

Through slots f in the walls of the perforation or chamber a project narrow spring-plates h into the chamber, the outer ends of these plates being riveted to the wings d of 55 the guides c . The receiver is located between the plunger C and anvil D of the machine.

A separator is attached to the chute some distance above the receiver. The rivets pass from a reservoir, where they are contained in 60 bulk, into the chute with their piercing ends upward, and before they reach the receiver are inverted by means of suitable mechanism, which it is not necessary to describe, since such mechanism forms no part of this invention. The separator is designed to arrest the 65 progress of the rivets as they slide down the chute in a row and allow but a single rivet to pass on and enter the receiver for each operation of the plunger.

70 No particular form of separator need be employed; but the one shown in the drawings, and designated by E, is simple and effectual.

When the machine is in use, the rivets collect in the chute above the separator, as 75 shown in Fig. 4, and as the plunger rises the plate u turns on its axis and draws upward the rod m , whereby the separator is caused to rotate slightly and the particular finger of the 80 separator which obstructs the passage of the rivets moves out of the way and the lowest rivet of the series passes down the chute; but only this single rivet is released at this time, because the next finger of the separator is 85 interposed across the passage below the succeeding rivet, and it and the other rivets above are thus held back till the plunger again rises and the separator is caused to rotate further, when the operation just described is repeated. As the rivet enters the receiver, having been 90 reversed, as before mentioned, its stem passes through the channel b and its head is supported in a horizontal position by the inner ends of the spring-plates h , where it remains ready to be driven by the plunger. The plunger, descending, meets the head of the rivet 95 and forces the rivet through the receiver, the plates h and guides c yielding gradually to the pressure of the plunger and keeping the rivet in a vertical position till, finally, the rivet is 100 driven through the garment or material beneath the receiver and upset either directly

against the anvil or within the shell of a button resting upon the anvil. The plunger then rises and the operation continues as described.

Having now described my invention, what I claim as new, and desire to secure by Letters Patent, is—

1. In the receiver of a rivet-setting machine, the combination of a chamber, *a*, with slots *f* in the walls thereof, and yielding plates *h*, attached at their outer ends to suitable supports, their inner ends projecting through the slots *f* and being adapted to support a rivet, substantially as and for the purpose described.

2. In the receiver of a rivet-setting machine, the combination of a chamber, *a*, with slots *f* in the walls thereof, yielding plates *h*, projecting through said slots and adapted to support a rivet, and pivoted arms *d*, to which said plates are attached, substantially as and for the purpose described.

3. In the receiver of a rivet-setting machine, the combination of the chamber *a* with slots *f* in the walls thereof, yielding plates *h*, projecting through said slots and adapted to support a rivet, and spring-regulated guides *c*, having wings *d*, to which said plates *h* are attached, substantially as and for the purpose described. 25

4. In the receiver of a rivet-setting machine, the combination of the arm *A*, provided with the chamber *a*, having slots *f* in the walls thereof, and the channel *b*, the yielding plates *h*, the pivoted guides *c*, and the spring *e*, substantially as and for the purpose described. 30

ALBERT M. WHITE.

In presence of—

LUCIEN F. BURPEE,
A. S. CHASE.
